UNITED STATES PATENT OFFICE.

DAVID Z. WRIGHT, OF CHILDRESS, TEXAS.

COTTON-CLEANING MACHINE.

Application filed February 5, 1921. Serial No. 442,759.

To all whom it may concern:

Be it known that I, DAVID Z. WRIGHT, a citizen of the United States, residing at Childress, in the county of Childress and

5 State of Texas, have invented new and useful Improvements in Cotton-Cleaning Machines, of which the following is a specification.

My present invention has reference to a 10 cotton cleaning machine.

The object is the production, in a machine of this character of means whereby the bolls of the cotton will be broken, the cotton cleaned, and separated in a single operation.

15 A further object is the production of a cotton cleaning machine in which the cotton is subjected to both a beating operation and influenced by suction of air whereby the same will be effectively treated when passing 20 through the machine and delivered therefrom in a properly cleaned condition.

A further object is the production, in a cotton cleaning machine, of means for preventing foreign matter entering the machine 25 with the cotton, and in which the cotton is first forced to pass between stationary and revoluble fingers, thereafter subjected to a suction of air in an outward direction, thereafter forced around a reticulated member to 30 further effect the cleaning thereof and to permit of foreign substances gravitating through the screen, and finally engaged by revoluble members for depositing the same in a cleaned condition to a suitable recep- 35 tacle.

The foregoing, and other objects which will appear as the nature of the invention is better understood, may be accomplished by a construction, combination and operative arrangement of parts, such as is illustrated by the drawings.

In the drawings:—

Figure 1 is an elevation of a cotton cleaning machine constructed in accordance with 45 this invention.

Figure 2 is a sectional view approximately on the line 2—2 of Figure 1.

Figure 3 is a sectional view approximately on the line 3—3 of Figure 2.

50 Figure 4 is a sectional view approximately on the line 4—4 of Figure 3.

Figure 5 is a fragmentary sectional view taken approximately in a line with one of the bolts which support the boll breaker.

55 Figure 6 is a detail perspective view of the adjustable boll breaker.

My improvement contemplates the employment of a casing 1 which is supported in any desired or preferred manner and which is designed to be used in connection 60 with the usual air suction line between the cotton supply and the fan. The casing 1, at the top thereof, has a chamber 3 to which is connected the pipe 2 of a suction fan (not shown). The cotton inlet conductor pipe is 65 indicated by the numeral 4. The pipe 4 communicates with a duct 5 that enters the side of the casing 1 a suitable distance below the chamber 3. The lower wall of the duct 5 has an opening adjacent to the inner end 70 thereof which is controlled by a swinging door 6 that swings into a receptacle 7. The outer wall of the receptacle is straight and is indicated by the numeral 8 and the inner wall is arranged at a downward and inward 75 inclination, as indicated by the numeral 9.

The bottom wall of the receptacle is indicated by the numeral 10, the outer wall of the said receptacle having an opening closed by a door 11. The receptacle is designed to 80 receive therein sticks and weighted foreign matter from the cotton as the same passes through the duct 5. The material is directed into the receptacle over the angle inner wall 9 of the said receptacle, and the passage 85 thereof is controlled by the door or valve 6, and the passage into the receptacle, indicated by the numeral 12 is controlled by the door or valve 6, the opening and closing of the said door being regulated in any desired 90 or preferred manner. The upper wall of the duct 5 projects a suitable distance into the casing. Between the said wall 13 and the angle wall 14 of the casing through which it enters there is a block 15, and at a suitable 95 distance away from the block the said wall 14 is provided with a cleat 16. Between the cleat and block there is an apertured plate 16'. The cleat and block provide guide-ways for the head portion 17 of the boll 100 breaker. The inner face of the head has projecting teeth or fingers 18 that pass through the apertures in the block 16'. The head has bolts 19 that pass through open- 105 ings in the wall 14 and said bolts are en-gaged by winged nuts 20 that also contact with the said wall 14. By this means the boll breaker may be adjusted inwardly or outwardly of its passage between the guides therefor, and preferably the bolts 19, be- 110 tween the head 17 and the inner face of the wall 14 are surrounded by springs 21 that

retain the fingers 18 in proper position for a purpose which will presently be apparent. To the cleat 16, at the inner end thereof, there is secured a segmental screen 22. This screen has its opposite end wall terminating at the inlet opening 23 in a cylindrical casting 24 for the outlet directing means for the cotton. At suitable points, the screen is supported in the casing 1 by cleats 25, and an air space is formed for the screen 24 at the top of the casing between the cleat 16 and a transversely arranged plate 26 in the said casing, the said plate being also connected with the screen. The plate 26, being arranged opposite and having its inner edge slightly below the air duct 5 also provides a means for directing the air forced thereagainst through the screen 22, the reticulated drum 27 and the cotton on said drum. The cleat 16 and the plate 26 are disposed each approximately an equal distance from the air outlet 2 for the casing.

In the casing there is a reticulated cylindrical drum 27. This drum is, of course, disposed inward of the screen 22, and is secured on a shaft 28 that passes transversely through the casing. The side members of the drum, inward of the periphery thereof are in the nature of flat rings 28' from which the spokes 29 radiate to the hub 30 that receives the shaft 28. On the ring plates 28 there are secured vanes 31, and on the periphery of the drum there are radially projecting fingers 32. The fingers are so arranged as to pass between the fingers 18 of the boll breaker. Both the top and the bottom of the casing have their walls inclined toward each other, and at the lower inclined walls there is an open cylindrical casing 33 in which is mounted on a shaft 34 a rotary dropper 35. In the casing there is also a rotary doffer 36.

The casing 1 is of an air tight construction. The suction fan draws the cotton to be cleaned through the pipe 4 into the casing. Suitable means is employed for constantly rotating the drum at a low speed, and suitable means are employed for rotating the dropper 35 and doffer 36. Any weighted foreign material drawn in with the cotton will drop, as previously described through the opening 12 into the receptacle 7 and may be removed therefrom through the door 11. The cotton drawn against the drum is contacted by the fingers thereof and is also contacted by the fingers 18 of the boll separator 17. This breaks the bolls and separates the cotton. The cotton is caused to slowly revolve around the screen on the drum, by engagement with the fingers of the drum therewith. The cotton passing between the points 16 and 26 is subjected to the strong suction of the air from the suction pipe, and at the point where the air entering the inlet 5 strikes the screen drum, the fanning of the

vanes is overcome by the high powered current to the suction fan, so that the air passes through the drum screen and between the vanes inside, revolving the drum and again passing through both screen and cotton upward through the chamber 3 and pipe 2. Thus the air currents go around only a portion of the circumference of the drum 27. As the air currents pass in and out of the drum, the vanes contacted by such currents will cause an outward fanning of the air through the bottom section of the screen 22 materially aiding the force of gravity in removing light as well as heavy foreign matter from the cotton. The cotton in its further passage around the drum will cause any small foreign particles to pass through the reticulated drum into the funnel-like bottom of the casing 1 and be delivered therefrom by the dropper 35. The main body of the cotton will pass over the drum to a position to be engaged by the blades of the doffer 36 which deliver the cotton therefrom through the outlet of the casing 24 to a suitable receptacle provided for this purpose.

It is believed that the foregoing description, when taken in connection with the drawings will fully set forth the construction, simplicity and advantages of the improvement, to those skilled in the art to which such inventions relate, without further detail description.

Having thus described the invention, what I claim, is:

1. In a cotton cleaning machine, in combination, a casing having a cotton inlet at one side thereof, a suction pipe at the top thereof, a doffer below the cotton inlet and a rotary dropper at the bottom of the casing, a boll breaker in the casing at the end of the cotton inlet, a segmental screen between the boll breaker and the doffer, a plate between the screen and the casing opposite the inlet, a reticulated drum in the screen having its outer periphery provided with projecting fingers and its inner periphery provided with vanes, and means for imparting a rotary motion to the drum, the dropper and the doffer.

2. In a cotton cleaning machine, in combination, a casing having a cotton inlet pipe at one side thereof, a suction pipe at the top thereof, a rotary dropper at the bottom thereof, a receptacle having an inner inclined wall below the cotton inlet, a valve controlling the passage between the receptacle and the cotton inlet pipe, a doffer below the receptacle, a toothed boll breaker at the inner end of the cotton inlet pipe, a segmental screen secured to the boll breaker and the doffer, a plate between the screen and casing opposite the cotton inlet pipe, a reticulated drum in the screen, said drum having outwardly projecting fingers and in-

- wardly directed vanes, and means for imparting motion to the drum and motion to the dropper and doffer.
3. In a cotton cleaning machine, in combination, a casing having a cotton inlet pipe at one side, a suction pipe at its top, a rotary dropper at its bottom and a rotary doffer below the cotton inlet, a boll breaker comprising a head having projecting fingers guided for said spring means, a segmental screen having its ends secured respectively to the boll breaker and the doffer, a plate secured 15 to the screen and casing opposite the cotton inlet pipe, a reticulated drum in the screen having outwardly projecting fingers and inwardly extending vanes, and means for imparting motion to the drum and motion to 20 the rotary dropper and doffer.
- 5 10 in the casing at the inner end of the cotton inlet, spring means influencing the boll breaker in one direction, adjusting means

In testimony whereof I affix my signature.

DAVID Z. WRIGHT.
